3 Claims. (Cl. 204—219)

This invention relates to electrolytic cells having mercury electrodes for electrolysis of alkali chloride solutions. More particularly, the invention relates to the construction of the inlet of a mercury-cathode chlorine cell having a mercury inlet passage channel disposed perpendicularly to the flow of the mercury in the electrolytic chamber.

I have previously proposed a mercury-cathode chlorine cell for carrying out electrolysis by causing mercury to flow from and perpendicularly to the longitudinal sides of a narrow electrolytic chamber as described in U.S. patent application No. 450,755 of Apr. 26, 1965. This electrolytic cell in comparison with a conventional horizontal mercury-cathode chlorine cell has a wide mercury flow path width and a short mercury flow path length and, in addition to being capable of accomplishing high-efficiency electrolysis with high current densities, has advantages such as the need for only a small quantity of mercury.

In an electrolytic cell of this character, the mercury sent by a pump first passes from the transverse direction of the electrolytic cell through a channel along the side in the longitudinal direction and then enters the interior of the electrolytic cell. In this case, since the flow of the mercury passing through the channel is caused to undergo an abrupt right-angle change in direction at the point of its entrance into the electrolytic cell, waves are formed at the flow surface and tend to cause breaks in the mercury flow.

It is an object of the present invention to provide improvement in the construction of the inlet of the electrolytic cell of the above stated character whereby to render uniform the mercury flow from the inlet passage channel into the electrolytic chamber and, moreover, to prevent wave motion in the flow surface in the electrolytic chamber.

According to the present invention there is provided a mercury-cathode chlorine cell of the character referred to above, characterized in that the mercury flowing from the mercury inlet channel is under a static head pressure and is introduced into the electrolytic chamber through a mercury flow guide slit comprising, in combination, a large number of small holes formed through the bottom plate of the electrolytic chamber above and in the direction of the inlet channel and a gap formed between the bottom plate and a flow guide plate fixed parallelly to the bottom plate and forming a ceiling covering the outlets of the small holes.

The nature, principle, and details of the invention will be more clearly apparent from the following detailed description with respect to preferred embodiments of the invention as illustrated in the accompanying drawings in which like parts are designated by like reference numerals.

In the drawings:

FIG. 1 is a simplified plan view showing one example of an electrolytic cell embodying the invention;

FIG. 2 is an elevational view in vertical section taken along the plane indicated by line IIa—II in FIG. 1;

FIG. 3 is an elevational view in vertical section taken along the plane indicated by line III—III in FIG. 1;

2

FIGS. 4 and 5 are elevational views in vertical section taken along planes equivalent to that indicated by line III—III in FIG. 1, respectively showing other examples of the electrolytic cell according to the invention; and

FIGS. 6(a), 6(b), and 6(c) are diagrammatic views respectively showing examples of small holes suitable for use according to the invention.

Referring to FIGS. 1 through 3, the principal operational part of the electrolytic cell shown is an electrolytic chamber 1 having a steel bottom plate 2 constituting a cathode. Along one side of the electrolytic chamber 1 and below the bottom plate 2, there is provided a mercury lower circuit channel 3, and numerous small through holes 4 are provided in a row in the bottom plate 2 above the channel 3, the row of holes extending over almost the entire length of the channel 3 and providing communication from the channel 3 to the electrolytic chamber 1. The diameters of the holes 4 are increased progressively by slight increments toward the end of the chamber 1 on the side of IIa so as to produce almost equal mercury flow rate through all holes 4.

A mercury guide plate 5 is disposed to project inwardly from the side wall of the electrolytic chamber 1 above the holes 4 with a gap 6 formed between the guide plate 5 and the upper surface of the bottom plate 2. A mercury outlet through 8 is provided along the side of the chamber 1 opposite the side of the channel 3 and is connected at the outlet end thereof to an amalgam decomposer 9 or denuding tower. The mercury recovered from the amalgam decomposer 9 is recirculated by a mercury pump 10 by way of a mercury circuit side passage 11 connected to the channel 3.

The mercury 7 which has been pumped by the pump 10 into the side passage 11 is caused by static head pressure to flow through the mercury lower circuit channel 3, from which the mercury passes through the holes 4 and emerges uniformly at the upper surface of the bottom plate 2. Here, the mercury has a flow velocity in the vertical direction due to the head pressure but is thereafter caused by the guide plate 5 to change its flow direction to that indicated by arrows and flows uniformly out from the gap 6.

That is, a flow guide slit is formed by the holes 4 and the gap 6, and the mercury flowing out of this flow guide slit already has a uniform velocity in the same direction as the mercury flow in the electrolytic chamber. Accordingly, even when impurities such as graphite particles and mercury butter are produced within the electrolytic cell in the vicinity of the outlet of the flow guide slit, such impurities are immediately swept along with the mercury flow and discharged. Therefore, there is no possibility of these impurities accumulating and lowering the efficiency of the electrolytic cell or of the generation of hydrogen within the cell.

As the mercury flows across the electrolytic chamber 1 to electrolyze brine, the amalgam thus formed is collected in the outlet through 8 and denuded by the amalgam decomposer 9, and the resulting mercury is again circulated by the pump 10 to the electrolytic cell.

In the above described electrolytic cell, it is possible also to omit the mercury circuit side passage 11 and to force the mercury by pump pressure directly into the inlet circuit channel 3. Furthermore, the small holes 4 are not necessarily limited to circular holes but may be circular, elliptical, oblong, trapezoid, or of some other suitable shape as indicated in FIG. 6. Moreover, in some cases, these holes may be aligned in a plurality of rows.

The surface of the flow guide plate 5 directly contacting the electrolyte is made of a chlorine-resistant, poor electrical conductor such as rubber, a synthetic resin, or a ceramic, but the lower surface to contact mercury is

preferably a material such as iron which has high wettability with respect to mercury.

While the foregoing description relates to an example of an electrolytic cell wherein the electrolytic chamber, as a whole, is almost horizontal, the present invention can be applied also to a vertical type electrolytic cell in which the primary electrolytic chamber is almost horizontal, and the secondary electrolytic chamber is inclined, as described in U.S. patent application No. 450,755 of Apr. 26, 1965. Examples of electrolytic cells according to the invention each having a horizontal electrolytic part and an inclined electrolytic part are shown in FIGS. 4 and 5.

The electrolytic cell of the above described construction and arrangement has the following effectiveness, utility, and advantages. According to the commonly held view in the prior art relative to electrolytic cells of the instant type, the width of the mercury flow film is limited to a maximum of approximately 3 metres and in most cases is from 0.8 to 1.5 metres, and, with any larger width, it has been extremely difficult to obtain a uniform mercury flow evenly over the entire flow film width.

I have found, however, that by causing the mercury under a static head pressure to be ejected through the small holes 4, which have a flow smoothening and equalizing effect, and changing the flow of the mercury thus ejected into a uniform flow in the transverse direction by means of a horizontal flow guide plate 5 as in the present invention, it is possible to force the mercury to flow out evenly over the entire mercury flow film width, which thereby may be increased to as much as 5 to 8 metres.

Accordingly, in the design of high-current electrolytic cells, it is not necessary to use an electrolytic chamber length of from 10 to 15 metres in the mercury flow direction, as in conventional practice, and it is possible to design an electrolytic cell of a length of only from 1 to 2 metres in the mercury flow direction to produce the same performance.

This feature of the present invention means that the retention time (or pass through time) of the mercury within the electrolytic cell can be shortened and the amalgam concentration can be constantly sustained at a low value, whereby the formation of mercury butter is diminished, and the small quantity of the mercury butter which may be formed is promptly discharged out of the cell. Accordingly, almost no hydrogen is generated.

Furthermore, since the mercury is subjected to forced flow, a high-velocity, thin, and smooth flow of mercury can be achieved with almost no inclination of the bottom plate of the electrolytic cell. Accordingly, the voltage regulation is facilitated, and it is possible to carry out the electrolytic process with the voltage at a low value.

Moreover, an extremely shallow depth of the electrolytic chamber is sufficient, whereby the manufacturing cost of the electrolytic cell can be lowered.

It is to be understood, of course, that the foregoing disclosure relates to only preferred embodiments of the invention and that it is intended to cover all changes and modifications of the examples of the invention herein chosen for the purposes of the disclosure, which do not constitute departures from the spirit and scope of the invention as set forth in the appended claims.

10. What I claim is:

1. In a mercury-cathode chlorine cell wherein mercury is caused to flow from a mercury circuit channel provided below an electrolytic chamber perpendicularly to the mercury flow direction along the bottom plate of the electrolytic chamber, through mercury flow guide means provided along a side wall of the electrolytic chamber, and into the electrolytic chamber to flow horizontally or down a slight incline along the upper surface of the bottom plate, mercury supply means to place the mercury flowing from the mercury circuit channel under a static head pressure and a mercury flow guide slit constituting said mercury flow guide means, said cell being characterized in that said mercury flow guide slit comprises, 15 in combination, a large number of small holes formed through the bottom plate of the electrolytic chamber above and in the direction of the mercury circuit channel and a gap formed between the bottom plate of the electrolytic chamber and a flow guide plate fixed parallel to 20 the bottom plate and forming a ceiling covering the outlets of said small holes.
2. A mercury cathode chlorine cell as claimed in claim 1, wherein the relative sizes, shapes, and spacing of the small holes of the mercury flow guide slit are selected 25 to produce a smooth mercury flow of uniform thickness across the entire width of mercury stream in the electrolytic chamber.
3. A mercury cathode chlorine cell as claimed in claim 1, wherein said static head pressure of the mercury supply 30 means is controllable.
